DIGITAL MULTIPLIER APPARATUS

Joachim Ernst Schulze, Oberfrohna, near Karl-Marx-Stadt, Germany, assignor to VEB Buchungsmaschinenwerk Karl-Marx-Stadt, Karl-Marx-Stadt, Germany

Application November 22, 1954, Serial No. 470,159

3 Claims. (Cl. 235—161)

This invention relates to a control and switching device for electronically controlling and performing calculations, particularly multiplications.

The known electronic arrangements of this class are generally complicated in structure as well as operation. Their control requires for instance a large number of counters consisting of tube systems and devices, in which a series of ten pulses, a second series of nine pulses and an additional series of single pulses, one of which successively occurs after the tenth pulse, have to be issued. Still another pulse is to be applied after 9×9 or 10×10 pulses to step up the calculating system for the next cycle and to ascertain the accumulation of pulses in the tube of the next digit of one factor when the product is to be obtained by repeated additions and this feeling out of digits.

This switching of one factor for this ascertaining process as well as the switching of the multiplicand register to the next place for entering the pulses in the correct decadic order is performed in wholly electronically operated machines by means of a considerable number of circuits acting as gates. While this arrangement affords the great advantage of practically timeless switching of counters, it is nevertheless expensive and cannot be regarded as economical in every instance. For example, the electronic tube-controlled calculators provided in connection with ordinary office machines operate at such a speed that the results cannot be utilized by them at the same speed. Furthermore, even electronic calculators of this type, which do not operate together with mechanically actuated office machines, are not economical, if the entering of the values to be handled by the calculators takes more time than the actual calculating operation, because high speed calculators cannot carry out more calculations in a given unit of time than an appliance having a lower calculating speed.

It is the object of the invention to provide a device which is simple to operate and inexpensive. According to the present invention this is accomplished by the use of two identical "left" and "right" side control counters, each of which is comprised of similar tube counters preferably having a capacity of 10 for operation with the decimal numbering system. These control counters control the feeling out of the multiplier in the multiplier accumulator, comprised of tube counters, and the multiplicand in the multiplicand accumulator, also comprised of tube counters. Transfer impulses from the left side control counter simultaneously are, firstly, fed into the multiplier accumulator as feeling out impulses to additionally switch it and thereby release transfer impulses over trigger and gate circuits for feeling out the multiplicand, secondly serve to further actuate the right side control counter, and thirdly actuate a product accumulator device for accumulating impulse groups in dependence upon the content of the multiplicand accumulator to present the product.

The employment of relays is an important feature of the invention, since relays can support a plurality of contacts which when closed offer almost no resistance to the

2

current and when opened show a very high resistance, and because relays may be connected in parallel or in series.

The very frequently occurring switching functions for adding single pulses in multiplication or subtracting them in division are therefore executed by electronic counters which are free of inertia while the advance of switching of the multiplicand, corresponding to multiplication by ten, is effected by relays. The number of multiplications by ten depends on the number of digits of the multiplier.

10 In case of a four-digit multiplier the multiplicand would be multiplied three times by ten and four relays would do the switching.

Although the form of construction of the device described with reference to the accompanying drawing relates to the decimal system, the invention is not restricted thereto, but can be applied also to other systems of counting. In the drawing

Figure 1 is a diagram of connection for the electronic control and switching arrangement;

15 Fig. 2, a diagram of the sequence of pulses of parts of the same arrangement as shown in Fig. 1 for a hundreds cycle;

Fig. 3, a diagram of connections of the sequential relay control;

20 Fig. 4, a diagram for applying pulses to start electronic control; and

Fig. 5, a diagram showing the use of a step-by-step relay.

Multiplication is performed by continuous addition and requires feeling out of the pulses accumulated in the multiplicand and multiplier registers. After the device has been switched in, the numbers to be worked have to be entered as usual.

The present example will be explained by using a three-digit multiplicand and a four-digit multiplier. Assumed 35 in the multiplicand register, in decimal counters Z0, Z1 and Z2 operating in the known manner of addition, the value "354" has been entered, that is to say the counter Z0 has been switched to "4," the counter Z1 to "5" and the counter Z2 to "3." The multiplier register has four 40 decimal counters Z25, Z26, Z27 and Z28 into which the value "2658" has been entered. The counter Z25 contains the value "8," counter Z26 the value "5," counter Z27 the value "6" and counter Z28 the value "2." These counters may be of the type described in U.S. Patent 45 2,624,507, columns 8 and 9. Their structure and function are well known and are not to be explained here in more detail.

When the arrangement is switched on, a pulse generator M is actuated, and in a known multivibrator connection

50 continuously gives off pulses. The pulse generator M consists in known manner of two tube systems A and B which at equal arrangement of both halves of this stopper oscillator alternately give off pulses, i.e., one pulse from one system B is always interposed between two pulses issued by the other system A, and vice versa. The pulses from system A are applied to gates G0 and G2, and the staggered pulses from system B to gates G3 and G4. These gates are of the type described by C. B. Tompkins and J. H. Wakelin in their book "High Speed

55 Computing Devices" (New York 1950) on page 37, chapter 4-3-3. These gates conduct current only when two positive impulses enter. The term "open gate" therefore relates to the condition wherein the negative bias of a grid has been lowered so far that an additional

60 single positive impulse applied to the gate is permitted to pass. The term "closed gate" relates to the condition wherein the grid has a negative potential and a positive impulse transmitted to the grid does not release the flow of current through the gate. These gates may be of the

65 same type and correspond to any known connection. Prior to each calculating cycle actuated at the beginning by a starting pulse and subsequently by a step up pulse a

flip-flop or trigger circuit FF0 representing one of the known bistable electronic connections is so connected that gate G0 is closed and thus does not let through pulses coming from system A. Flip-flop or trigger circuit suitable for the purposes of the present invention is described in "Radar Electronic Fundamentals" (Bureau of Ships, U.S. Navy Department, 1946), p. 193. Flip-flop or trigger circuits are referred to herein as "flip-flops." Further, a flip-flop FF1 is so connected as to open gate G1 and close gate G2. This arrangement prevents the introduction of pulses issuing from system A into the connection, since both gates G0, G2 are closed. Another flip-flop FF3, by its connection, opens gate G4 and closes gate G3, so that the pulses continuously issuing from system B of generator M pass through gate G4 over a lead to flip-flops FF10, FF11 and FF12 which are switched so that gates G10, G11 and G12 are closed. The pulses from system B are applied also to flip-flop FF5 which is switched as will be described later. After these switching operations pulses supplied by system B also remain ineffective.

A product accumulator comprised of tube counters Z10 to Z16 is connected over contact switches a0 to a2, b0 to b2, C0 to C2 and d0 to d2, switched by relays A, B, C and D, with the arrangement over gates G10, G11 and G12. At energization of relay A, for instance, contacts a0, a1 and a2 will therefore be closed, whereby counter Z10 is connected to gate G10, counter Z11 to gate G11 and counter Z12 to gate G12. When relay B is energized, counter Z11 is connected over contact b0 to gate G10, counter Z12 over contact b1 to gate G11 and counter Z13 over contact b2 to gate G12. At energization of relays C or D counters Z12 to Z15 will be connected according to the arrangement of contacts c or d. Energization of a relay, however, does not involve merely the switching of contacts a to be applied to counters Z10 to Z16, but also of contacts a8 and a9 to d8 and d9 applied to a multiplier accumulator comprised of tube counters Z25 to Z27. For example, at energization of relay A the counter Z25 is connected to the arrangement over contacts a8 and a9. 40 gate G1 and flip-flop FF1, at energization of relay B the counter Z26 and so forth. It is to be understood of course that only one relay is energized at a time.

The relays are controlled as follows:

By the starting contact S₁, as indicated in Fig. 3, the relay A is pulled up and continues to hold itself over the operating contact a13, rest contacts b14 and d14. After completion of the first electronic cycle of operation a short pulse is applied over the amplifier RV and energizes relay B over the now attracted rest contact a11. After this pulse has faded out the relay B pulls up and holds itself over the operating contact b13 and the rest contacts c14 and d14. Simultaneously, the rest contact b14 is opened and the energization of relay A falls off.

When the second electronic operating cycle is finished, the next pulse comes over RV and over the now closed operating contact b11 energizes relay C which holds itself over operating contact c13 and rest contact d14. By pulling up relay C the rest contact c14 is opened, so that relay B drops. At the end of the third cycle the operating contact c11 is closed and relay D is energized by the pulse coming from amplifier RV and holds itself over operating contact d13, so that the rest contact d14 is opened and relay C drops.

When the multiplication 354×2658 is to be performed, the relay A is energized by the starting pulse, whereby the contacts a0, a1, a2, a8 and a9 are closed and the counter Z10 is connected to gate G10, counter Z11 to gate G11, counter Z12 to gate G12 and counter Z25 to gate G1 and flip-flop FF1.

Electronic control is initiated over delay trigger VF7 as follows:

By pulling up relay A (Fig. 4) operating contact A15 is closed and the condenser C positively charged over the resistance R is suddenly discharged by the closing of the

contact a15 and a negative pulse is transferred over condenser C1 to the delay trigger VF7. At the beginning of the second cycle the relay A falls off and thus closes the rest contact a16, the operating contact b15 being closed also. The condenser C has been charged over the resistance R between the opening of contact a15 and the closing of contact b15 and is now discharged once more, whereby another pulse is transferred over condenser C1 to delay trigger VF7. In similar manner pulses are put out by the relays C and D.

The pulse slightly delayed by trigger VF7 then switches flip-flop FF0 to open gate G0. The pulses issuing from system A of generator M can now pass through the open gate G0 to the left side control counter Z8 set at "0." The first pulse switches the left side control counter Z8 to "1," the second to "2," etc., the tenth to "10" or "0," and this is the first pulse to leave left side control counter Z8, pass to right side control counter Z9 set at "0" and to switch it to "1." At the same time the pulse coming from left side control counter Z8 is applied over the opened gate G1 and contact a8 to the counter circuit Z25 set at "8" and switches it to "9." During the following second tens cycle of the pulses issuing from system A the left side control counter Z8 set at "0" is stepped up again in the manner described, and the tenth pulse of this cycle switches left side control counter Z8 to "10" or "0," whereupon likewise a pulse switches right side control counter Z9 from "1" to "2" and counter Z25 from "9" to "10" or "0," so that this counter also supplies a pulse which over closed contact a9 switches flip-flop FF1, whereby the gate G1 is closed and gate G2 opened.

The counter circuit Z25 has now determined that the multiplicand "354" has to be added eight times, corresponding to the filling up of the right side control counter Z9 to "10" or "0." This successive addition is controlled by the following pulses issuing from system A of which the twenty-first pulse is transferred through gate G0 to left side control counter Z8 and over gate G2 and a lead to the multiplicand accumulator comprised of tube counters Z0 to Z2. By this pulse the counter Z0 set at "4" is switched to "5," counter Z1 from "5" to "6" and counter Z2 from "3" to "4." This twenty-first pulse from system A and first pulse over gate G2 further switches the flip-flop FF3, whereby the gate G4 is closed and gate G3 opened.

The pulses from system B pass therefore now over gate G3 to gates G10, G11 and G12 which, however, are still so connected that they cannot let these pulses through. Only when the pulses derived over gate G2 from system A switch the counters Z0, Z1 and Z2 to "10" or "0" will these counters at different times, according to their position, apply a pulse to their subordinated flip-flops FF10 to FF12, whereby they are switched to open the gates G10 to G12, that is to say, the fifth pulse of the third tens cycle switches the counter Z0 to "9," counter Z1 to "10" or "0" and counter Z2 to "8." Due to the switching of counter Z1 to "0," the flip-flop 11 is switched and gate G11 opened, so that the fifth pulse of the third tens cycle received from system B is entered over gates G3 and G11 and over closed contact a1 into the product counter Z11 and sets it from "0" to "1." The sixth pulse from system A of this tenth cycle sets counter Z0 to "10" or "0," whereby the flip-flop 10 is switched and gate G10 opened and the sixth pulse of this tens cycle from system A enters over gates G3, G10 and G11 and over closed contacts a0 and a1 into the counters Z10 and Z11, setting counter Z10 from "0" to "1" and counter Z11 from "1" to "2." The seventh pulse from system A of the third tens cycle sets counter Z2 also at "10" or "0," whereby flip-flop 12 is switched and gate G12 opened, owing to which the seventh pulse from system B can enter over gate G12 and closed contact a2 into the counter Z12 set at "0" and reset it to "1." Simultaneously, the counter Z10 is set to "2" and counter Z11 to "3." The eighth and ninth pulse of this tens cycle

from system B set counter Z10 to "4," counter Z11 to "5" and counter Z12 to "3." The tenth pulse from system A sets counter Z0 again to "4," Z1 to "5," Z2 to "3" and left side control counter Z8 to "10" or "0," whereby right side control counter Z9 is set from "2" to "3" and flip-flop 3 switched, so that gate G3 is closed and gate G4 opened with the result that the tenth pulse of the third tens cycle from system B passes over the opened gate G4 and switches flip-flops 10 to 12 to close gates G10 to G12. From the thirty-first pulse issuing from system A this switching operation is repeated up to the hundredth pulse which is applied to left side control counter Z8 and leaves it as tenth pulse, thereby switching right side control counter Z9 to "10" or "0," whereby flip-flops 5 and 3 are switched. The pulse issuing from system B after this hundredth pulse passes over gate G4 and switches flip-flops 10 to 12 as well as flip-flop 5. This causes a pulse to issue from flip-flop 5 and to switch flip-flop 1, so that gate G1 is opened again and gate G2 closed. The same pulse from flip-flop 5 switches flip-flop 0, whereby gate G0 is closed, and a control pulse issuing from the other side of flip-flop 0 actuates the relay control over amplifier RV as stated, and after corresponding amplification of this pulse the relay B is energized, so that the switch contacts b are closed, relay A falls off and switch contacts a are opened again.

Before starting the second hundreds cycle the counters occupy the following positions:

The multiplicand registers show again Z0 set to "4," Z1 to "5" and Z2 to "3." The multiplier register shows Z25 set to "0," as it has been subjected to the ascertaining operation described, Z26 set to "5," Z27 set to "6" and Z28 set to "2," but the product accumulator, due to the continuous eightfold addition of the multiplicand register, contains the value "2832," since the counter Z10 has been set to "2," counter Z11 to "3," counter Z12 to "8" and counter Z13 to "2." Counters Z14 to Z16 are still set to "0." As these product counters are accumulative registers, they apply at a "10" or "0" connection, over a known buffer circuit or the like, a pulse to the next following counter and advance it one place.

After the relays have been switched the initiation of the new hundreds cycle must be slightly delayed by the trigger VF7 to let the relays come to rest when contact chatter has ceased to insure safe passage of the electronic pulses. In order to obtain this delay at the start of the new hundreds cycle, a delay trigger VF7 is provided having the form of a flip-flop capable of operating according to any known retardation connection and returnable to initial position some time after energization. Besides providing the delay trigger VF7 it is necessary to prevent electronic connection in the various counters due to the actuation of the relay contacts. For this reason, all leads without exception, which run over relay contacts, are kept at a predetermined D.C. voltage level, so that no jump in the voltage can occur at the closing or opening of contacts. This connection is shown for instance in Fig. 1 on the lead from gate G10 to counter Z10 and over condensers C1 and C10, which insures D.C.-like blocking, and the predetermined potential is provided over resistances R1, R10. For the sake of greater clearness this connection is shown only once.

The pulse delayed by trigger VF7 switches the flip-flop 0 at the beginning of the new hundreds cycle to open gate G0, whereby pulses from system A can be transferred again over gate G0. The connection operates as described, but the tenth pulse enters through left side control counter Z8 over contact b8 into counter Z26 set to "5" and switches it to "6." The twentieth pulse switches this counter to "7," the thirtieth to "8," the forty to "9" and the fiftieth to "10" or "0" so that this counter, over contact b9, supplies a pulse to flip-flop 1, switches it and opens gate G2, whereby the remaining five tens cycles from system A pass over gate G2. The pulses derived from system B after switching flip-flops

10 to 12 and opening gates G10 to G12 pass over gate G10 and contact b0 to counter Z11 and/or over gate G11 and contact b1 into counter Z13. After the hundred pulses of this second hundreds cycle, owing to the five-fold continuous addition of the multiplicand, the product accumulator thus holds a value of "20532."

At the starting of the third hundreds cycle the relay C is energized and relay B dropped, whereby contacts b are opened and contacts c closed. After the opening of gate G0 always the tenth pulse issuing from left side control counter Z8 enters now counter Z27 over contact c8. The fortieth pulse coming from system A is the fourth one issuing from left side control counter Z8 and switches counter Z27 to "10" or "0," whereby this counter is caused to issue a pulse over contact c9 and thus switches flip-flop 1 as described. The control operates then as stated, and from the fifth to the tenth tens cycle, according to position "354" of counters Z0 to Z2, pulses enter over gate G10 and contact c0 into the counter Z12, over gate G11 and contact c2 into counter Z14, so that after the hundred pulses of this third hundreds cycle a value of "232932" is contained in the product accumulator.

To feel out the pulses of the fourth place of the multiplier, that is, of counter Z28, a fourth hundreds cycle has to begin. The relay D is energized and relay C drops, whereby contacts c are opened again and contacts d closed, so that counter Z28 can be examined to find out how often the multiplicand has to be added over and over again. These controlled pulses enter, as described, over gate G10 and contact d0 the counter Z13, over gate G11 and contact d1 counter Z14 and over gate G12 and contact d2 counter Z15 and thus represent the final result "940932" of this multiplication.

Instead of relays A-D a step-by-step relay may be used. Fig. 5 shows how such a relay is to be interposed in the connection. The insertion of this relay affords, moreover, the advantage that the sequential control is automatically insured by the very nature of the relay which can be started also by amplifier RV.

I claim:

1. A multiplying apparatus comprising a first pulse generator producing a plurality of periodic pulses, a second pulse generator producing pulses alternating with the pulses of said first generator; a plurality of electronic decade counters having pulse responsive inputs, each adapted to recycle upon reaching its digital capacity and emit an output pulse at each recycle; one of said counters being a first control counter responsive to said first pulse generator; another of said counters being a second control counter identical with said first control counter and connected to said first control counter to respond to recycling pulses of said first control counter; a plurality of gates alternately adjustable between an open position to pass pulses and a closed position adapted to block pulses; a first of said gates operatively connecting the input of said first control counter and said first pulse generator; a plurality of said counters being multiplier counters arranged in an ascending decade order and each adapted to have a digit of a multiplier entered therein, a second of said gates operatively connecting said multiplier counters to the output of said first control counter; trigger means connected to the output of said multiplier counters and to the output of said second control counter and adapted to open said second gate in response to recycling of said multiplier counters and to close said second gate in response to recycling of said second control counter; switch means actuated in response to the output of said second control counter including a plurality of multiplier switches sequentially connecting said second gate to the output and said trigger means to the input of each of said multiplier counters in ascending decade order; a plurality of said counters being multiplicand counters arranged in order of ascending decade power and adapted to have a digit of a multiplicand entered therein; a third

gate connected to said trigger means for operating alternately to said second gate and operatively connecting said first pulse generator and said multiplicand counters; a plurality of said counters being connected in series to form a multiple decade product accumulator; a plurality of said gates being multiplicand gates each corresponding to a multiplicand decade and each operatively connecting one decade of said product counters to said second pulse generator, means for opening each of said multiplicand gates in response to recycling of the corresponding one of said multiplicand counters and closing said gates in response to recycling of said first control counter; a plurality of said switches being ganged product switches initially connecting each of said multiplicand gates to the product counter decade of corresponding order and progressively switching each of said multiplicand gates to the product counter decade of next higher order in response to recycling of said second control counter.

2. A multiplying apparatus as set forth in claim 1 wherein said means for opening and closing said multiplicand gates includes a pair of oppositely operative gates connected to change condition for one pulse duration in response to transfer pulses from said first control counter, one of said pair of gates connecting said second pulse generator to said multiplicand gates, the other of said gates connecting said second pulse generator to close said multiplicand gates.

3. A multiplying apparatus comprising a first pulse generator for generating a succession of electrical counting pulses; a pair of identical decade control counters connected in series each operative to recycle and release a transfer pulse upon reaching its digital capacity; a multiplier register including decade counters arranged in ascending decade order, a second pulse generator, a first gate connecting a first of said control counters to said first pulse generator, a second gate connecting said multi-

plier register to said first control counter, switch means connecting one of said multiplier counters to said second gate and adapted to switch to the counter of next higher decimal order in response to recycling of the second of said pair of control counters; said second control counter of said pair of control counters being connected to receive transfer pulses from the first of said control counters; a first trigger circuit responsive to transfer pulses from said multiplier register; said first trigger being connected to said second gate for opening and closing it, a third gate responsive to said first trigger circuit in a sense opposite to said second gate; a multiplicand register including decade counters; said third gate connecting said first pulse generator and said multiplicand register; a second trigger connected to said first pulse generator; a fourth gate connected to said second trigger circuit, a fifth gate connected to said second trigger circuit; a plurality of multiplicand trigger circuits and gates; connections leading from said second pulse generator to said fourth and fifth gates to transfer pulses to said multiplicand trigger circuits and said multiplicand gates; connections leading from said multiplicand register to said multiplicand trigger circuits for switching them; a product accumulating means including decade counters; connections from said product accumulating means to said multiplicand gates to receive pulses from said second pulse generator; a third trigger circuit; said second control counter and said third trigger circuit being connected to said first gate for disconnecting first pulse generator; said third trigger being connected to said first trigger for closing said first gate.
